Attorney, Agent, or Firm—Auzville Jackson, Jr.

[57] **CLAIM**

The ornamental design of a constant flow selector valve, substantially as shown and described.

DESCRIPTION

FIG. 1 is a top plan view of a constant flow selector valve embodying my new design;

FIG. 2 is a bottom plan view thereof;

FIG. 3 is a front elevational view thereof;

FIG. 4 is a left side elevational view thereof;

FIG. 5 is a front perspective view thereof;

FIG. 6 is a rear elevational view thereof; and

FIG. 7 is a right side elevational view thereof.

FIG.1

FIG.2

FIG. 5

FIG. 3

FIG. 6

FIG. 4

FIG. 7
